UNITED STATES PATENT OFFICE.

KARL DELLGREN, OF VÄSTERVIK, SWEDEN.

GUARD FOR GRINDING-WHEELS AND SIMILAR ROTATING BODIES.

1,335,223.

Specification of Letters Patent. Patented Mar. 30, 1920.

Application filed December 26, 1918. Serial No. 268,368.

To all whom it may concern:

Be it known that I, KARL DELLGREN, a citizen of the Kingdom of Sweden, residing at Västervik, Sweden, have invented 5 new and useful Improvements in Guards for Grinding-Wheels and Similar Rotating Bodies, of which the following is a specification.

This invention relates to guards for grinding wheels and similar rotating bodies.

The principal object of the invention is to provide a guard of this kind adapted to prevent damages caused by the flying off of the rotating body.

Another object is the provision of such a guard possessing a certain degree of elasticity and adapted to be adjusted in conformity with the diameter of the rotating body according as its diameter decreases, 20 owing to the wear of the body.

The invention consists, chiefly, in the combination of an adjustable frame, transverse bolts in said frame, two adjustable arcuate plates overlapping each other and bearing 25 against said bolts, and one or more elastic members, as for instance wires, attached to said frame and surrounding said plates, so as to press them against the transverse bolts of the frame.

A preferred embodiment of the invention is illustrated in the accompanying drawing in which—

Figure 1 is a side-view of a guard constructed in conformity with the invention. 35 Fig. 2 shows a front view of the same guard.

Referring to the drawing, the dotted line 1 denotes a rotating body for instance a grinding wheel. Placed at a distance apart from said body and extending along its periphery is a strap made for instance of sheet iron or the like. In the embodiment 40 shown in the drawing the strap consists of two parts 2 and 3 overlapping each other at the ends 4. Bearing against the outer side of the strap 2, 3 are one or more elastic members, as for instance wires, spiral springs or the like, extending in peripheral direction. In the embodiment shown said elastic members consist of two wires 5 and 45 6 placed side by side. The guard constructed in the manner described is supported by 50 a frame arranged as follows:

Disposed at each side of the rotating body 1 and at the center thereof is a plate 7 and 55 8 respectively, each of said plates being pro-

vided with an aperture 9 enabling the frame to be slid onto the shaft of the rotating body. Secured to each plate 7 and 8 are a number of arms, two of which 10 and 11 at each plate are connected with the corresponding plate, the other ends of said arms 10 and 11 being spaced apart so as to render the periphery of the grinding wheel accessible through the interspace between the arms 10 and 11. Passed through the last- 60 named ends of the arms 10 and 11 are bolts 12 and 13, to which, on the one hand, the wires 5 and 6 and, on the other hand, the free ends of the strap 2, 3 are secured. Thus the bolts 12 and 13 together with the 65 arms 10 and 11 support the ends of the wires 5 and 6 and the free ends of the strap 2, 3. Extending from each plate 7, 8 are two arms 14 and 15 secured to the corresponding plate and through the outer ends 70 of which are passed bolts 16 and 17 respectively supporting other points of the strap 2, 3. Furthermore, the ends of a stirrup 18 placed outside the strap 2, 3 are attached to the plates 7 and 8. As will appear from 75 the drawing, the wires 5 and 6 are wrapped about the portion 19 of the stirrup situated outside the strap, the wires being prevented from sliding on the strap 2, 3 by means of a plate 20 bearing against the wires and 80 retained against the same by screw 21 85 screwed into the portion 19.

To the plate 7 or to both plates 7 and 8 a rod or arm 22 may be fixed by means of which the guard may be attached to the 90 frame supporting the rotating body.

In all the arms 10, 11, 14 and 15 and in the stirrup 18 apertures 23 are provided. By placing the screws 24 connecting the arms and the stirrup with the plates 7 and 95 8 in different apertures 23, the guard may be adjusted, as desired, to the decrease of the diameter of the rotating body owing to the use of the same.

The principal advantage attained by a 100 guard constructed as described above consists in this that the guard, on account of the elasticity of the members 5 and 6, is capable of catching the fragments in case of the rotating body flying off, without necessitating the strap 2, 3 to be made of a material possessing a particularly high degree 105 of resistibility.

Having now particularly described and 110 ascertained the nature of my said inven-

tion and in what manner the same is to be performed, I declare that what I claim is:—

1. A guard for grinding disks and the like, comprising a frame, arcuate adjustable plates mounted on the frame concentric to the disk, and reinforcing wires extending around the plates and connected at their ends to the frame thereby binding the plates onto the frame.
- 10 2. In a guard for grinding disks and the like, a frame consisting of side plates having apertures to receive the shaft of the disk,

a stirrup connecting the plates on opposite sides of the disk, arms connected to the plates extending beyond the periphery of the disk, bolts connecting the arms on opposite sides of the disk, arcuate plates passing between the disk and stirrup, and wires connected to the stirrup extending over the arcuate plates for binding the latter onto the connecting bolts.

In testimony whereof I have signed my name.

KARL DELLGREN.
